Application November 12, 1938, Serial No. 239,908

4 Claims. (Cl. 40—7)

This invention relates generally to containers and particularly to a package adapted specifically for sanitary napkins.

5 Sanitary napkins are almost universally employed by women as an effective absorbent of the catamenial flow from the generative organs.

10 This physiological periodic phenomenon is considered such a personal female function that a psychological resistance complex exists in the mind of the female against considering the purchase of napkins as a usual commercial transaction. This, together with the modesty of women, has established a recognized and well-practiced mode of selling sanitary napkins.

15 It is now the common practice among merchants to wrap the containers of sanitary napkins in ordinary wrapping paper long prior to their delivery, so that when a woman purchases sanitary napkins she is delivered a wrapped package. That such a practice does have the effect of reducing the uneasiness of the purchaser of such a product is evident. However, many women continue to feel uneasy when carrying a package of napkins even though it has been wrapped 20 in plain paper. This uneasiness is usually caused by the belief that the contours of the package containing the napkins are generally recognized as those of a package containing napkins. To obviate this feeling, many women in purchasing napkins request that the merchant remove the napkins from their original container. Although the removal of the napkins from their original container satisfactorily solves the previously mentioned problem, such practice is very undesirable. Firstly, the removal of the napkins from the original container exposes them to the likelihood of contamination during the transfer from the container to the wrapping paper. Secondly, oftentimes the merchant is too busy to make the 25 transfer himself, and thus the purchaser is forced to do it herself, resulting in a condition which the transfer itself was intended to obviate to the extreme embarrassment of the purchaser. Thirdly, it is not unlikely that the purchaser is 30 extremely embarrassed during the transfer of the napkins from the original container to wrapping paper because people entering the store become witnesses to the transfer.

35 There are many women who are so secretive about the use of sanitary napkins that, as soon as they arrive home with a package containing napkins, especially a package bearing identifying indicia of the product, they remove the napkins from the package. Other women, although 40 not motivated by shyness, remove the napkins

from their container because of the difficulty of placing such an unyielding shape as a cardboard box in a drawer.

It is within the contemplation of our invention to eliminate the structural disadvantages of the present type of containers for sanitary napkins and to provide a package for sanitary napkins which will completely eliminate the very conditions which give rise to the uneasiness of the women in purchasing a product of the type herein referred to.

One of the objects of the invention is to provide a package for sanitary napkins which possesses a band incorporating thereon the trade-mark and product identifying indicia of the manufacturer of the product and which has such structural characteristics that said indicia can be completely covered at the time the package is delivered to a purchaser.

Another object of the invention is to provide a package for sanitary napkins which does not possess the characteristic contours of the containers now employed by napkin manufacturers and distributors.

Still a further object of the invention is to provide a package for sanitary napkins which permits the complete elimination or coverage of all identifying indicia of the contents.

Still another object of the invention is to provide a package which, though initially containing the trade-mark of the manufacturer or distributor and product identifying indicia thereon, may readily be altered so that said indicia is covered, the package thus losing the identity of the product as well as of the manufacturer.

Still another object of the invention is to provide a package having a removable band thereon, said band containing the identifying indicia of the manufacturer and the product.

Another object of the invention is to provide a package for sanitary napkins, possessing structural characteristics which obviate the necessity of removing the napkins therefrom when the purchaser seeks to destroy the identity of the contents of the package.

A similar object of the invention is to provide a package which will, under normal circumstances, permit the purchaser thereof to retain the contents therein without fear of embarrassment.

A further object of the invention is to provide a package for sanitary napkins which maintains the contents in a fresh condition and which prevents moisture from entering therein.

Still another object of the invention is to pro-

vide a package for sanitary napkins which has means for opening the package and sealing the same when desired.

The advantages resulting from the use of packages embodying the principles of our invention and other objects may come to mind when reading the detailed description which follows, and for a full understanding of the invention it is essential that the accompanying drawings, which are a part of the specification, be examined and in which there is shown several views of packages embodying the principles of our invention.

In the drawings, in which corresponding parts are given identical reference characters,

Figure 1 is a perspective, rear end view of a package embodying the invention and showing the trade-mark and product identifying indicia on the band;

Figure 2 is a perspective, front end view of a package embodying the invention and showing the trade-mark and product identifying indicia on the band completely covered;

Figure 3 is a perspective, front end view of a package embodying the invention with the band removed to show the package sealing means employed;

Figure 4 is a side elevation of the package embodying the invention and showing the relation of the band to the remainder of the package, when in position as shown in Figure 1;

Figure 5 is a side elevation of a package embodying the invention and showing the relation of the band to the remainder of the package, when in position as shown in Figure 2;

Figure 6 is a perspective view of a package embodying the invention and showing the relation of that portion of the band which is movable to cover the trade-mark and product identifying indicia shown in Figure 1 so that the band will appear as shown in Figures 2 and 5;

Figure 7 is a sectional, transverse view of a package embodying the invention and showing the interior liner of the package and the relation of the band to the exterior portion of the package; and

Figure 8 is a perspective, plan view of a package embodying the invention, showing a band having slightly modified characteristics but primarily positioned differently from the band shown in Figures 1 to 7 inclusive.

The container, preferably made from a fibrous material, such as cardboard or paper, and in the shape and possessing the dimensions of a standard paper bag, is generally designated by reference character A. Although the present preferred practice is to employ a paper bag of standard dimensions, it should be understood that it is possible to employ a container made of different material provided its dimensions and shape do not simulate or suggest the dimensions and shape of the containers now employed for sanitary napkins. It is advisable to point out that the material used in fabricating the container must possess yielding characteristics so that it may fit into various locations and also be reducible in proportion as the contents are removed.

Referring to Figure 7, bag A consists of the usual side walls 1 and 2, bottom 3, top 4 and closed end 5 (see Figure 1). A liner bag, designated generally by reference character B, is disposed within and fits into bag A so that its side walls 6 and 7, bottom 8, top 9, and closed end 10a (not shown) coincide with the side walls, top, bottom, and closed end of bag A. The liner bag 75 is made of a material which is moisture resistant

and which will prevent moisture from entering into the interior and being absorbed by the napkins, whose cellulose or other filler possesses highly absorbent qualities, when the bag A and liner B are sealed. The liner bag B must also maintain the sanitary napkins 10, shown in position in Figure 7 within the interior of liner bag B, in a sterile and fresh condition.

After the sanitary napkins 10 have been inserted into the bag A and confined within the liner bag B, the fronts or open ends of the bags A and B are folded as shown in Figure 3. Triangular portion 11 laps over triangular portion 12, permitting a strip of thin material 13 to be secured to triangular portion 11. The strip of material 13 has one face thereof covered with an adhesive which is pressure responsive and which therefore permits the removal of the strip from the surface to which it is attached without apparently damaging said surface. Strip 13 extends upwardly and has a portion thereof removably secured to the top 4 of bag A for a short distance. A tab 14 is formed within the strip 13 by folding one end thereof upon itself. Since the adhesive employed has the inherent quality of permitting the removal of the strip 13 from its position upon the top 4 of bag A by exerting a slight upward pull on the tab 14, it can be appreciated that the interior of bag B can be easily reached without in any way damaging or impairing either bag A or B or the strip 13. Furthermore, since the adhesive on the strip 13 is pressure responsive, the bag can be resealed by applying pressure to the strip. By this construction the contents may be kept in a fresh and sterile condition regardless of the number of times the bags A and B are opened.

A pair of flat strips of thin material, generally designated by reference characters C and C', are joined to each other as shown at 15 in any desirable manner. The strips of material C and C' may be made of cardboard, paper, or of any other fibrous material; and although the preferred construction calls for the use of two strips of material joined together by an adhesive, or by any other means, the use of a single strip of material is possible. The two strips of materials C and C' are interlocked and removably joined to each other, as shown at 16, in any well-known manner and, when so joined, form an endless band which is removably disposed on the outside of bag A. The band C—C' thus formed is placed longitudinally of the bag A and when so placed forms a pair of parallel walls 17 and 18, a top 19 and a bottom 20. While band C—C' tends to bind and strengthen the package, it is in no way directly connected to the bag A and may be readily removed therefrom without in any way altering the package or exposing its contents. It is obvious that ornamentation may be placed on the band C—C' and trade-mark and product identifying indicia 21 is in fact placed upon the top 19 as shown in Figure 1. Since one of the important objects of the invention is to cover the trade-mark and identifying indicia of the product so that a purchaser will not be embarrassed thereby, strip C, which forms a part of the band C—C', has an extension strip which forms, when positioned as shown in Figures 1 and 4, wall 22 and bottom 23. Wall 22, when positioned as shown in Figures 1 and 4, is in intimate parallel relation to wall 17; and bottom 23, when positioned as shown in Figures 1 and 4, intimately contacts bottom 20.

A tongue 24 is formed at the end of the extension strip comprised of wall 22 and bottom 23.

This tongue is inserted into slot 25 formed at the juncture of wall 18 and bottom 20, best shown in Figure 6. By this means the bottom 23 is retained in intimate relation to bottom 20 of the endless band C—C'. The package is assembled and marketed in the form heretofore described and shown in Figures 1 and 4 with the trade-mark and product identifying indicia exposed to view of prospective purchasers and the public and may be displayed in any manner desirable. When it is desired to cover the trade-mark and product identifying indicia so that a purchaser may carry the package out of the store without fear of embarrassment and without altering the package, the tongue 24 is removed from slot 25 and the bottom 23 and wall 22 are moved into the position shown in Figures 2, 5, and 6. This change in position of the extension strip (wall 22 and bottom 23) is facilitated by forming a crimp 26 transversely at the juncture of top 19 and wall 22 and a similar crimp within bottom 23, as shown at 27. After the extension strip is moved into the position shown in Figures 2, 5 and 6, tongue 24 is reinserted into slot 25. This rearrangement of the extension strip results in the complete coverage of the trade-mark and product identifying indicia without in any way altering the structural characteristics of the bag A or the band C—S'.

In Figure 8 is shown a package which has a band C—C' possessing slightly different structural characteristics. Instead of a crimp 26 being formed at the juncture of wall 22 and top 19, a transverse perforation 28 is formed therein and instead of placing the groove 25 at the juncture of side wall 18 and bottom 20, it is placed at the juncture of wall 18 and top 19 and finally, instead of placing the trade-mark and product identifying indicia on top 19, it is placed directly on top 29. Furthermore, the extension strip from which top 29 is formed remains in the position shown in Figure 8 at all times and never assumes the two positions taken by the extension strip in the preferred disclosure. When it is desired to remove the trade-mark and product identifying marks from the package before delivery of same to the purchaser, the tongue 24 is removed from slot 25 and the top 29 is torn from the remainder of band C—C' at the perforations 28. Thus the package is in no way altered and the purchaser is assured of a package containing sanitary napkins which has no tell-tale marks thereon which are likely to cause embarrassment.

From the foregoing description it will undoubtedly appear that the invention as described fulfills the objects set forth herein. While the specification describes and the drawings disclose in detail the present and preferred construction of the invention, it should be understood that, in practice, deviations can be made by those skilled in the art to which this invention relates without departing from the spirit of the invention. It should therefore be understood that we consider as our own all such modifications and

adaptations of this invention as fairly fall within the scope of the appended claims.

Having thus described our invention, what we claim as new and desire to secure by Letters Patent is:

1. A band to be used on a package of the class described comprising, two elongated strips of fibrous material, of different lengths, the shortest of the strips having one of its ends adhesively secured to the longest strip and having the other 10 of its ends disengageably locked to one of the ends of the longest strip and, when so locked, forming an endless rectangular band, the longest strip possessing, on a portion thereof, trade-mark and product identifying indicia, and adapted to 15 be folded upon itself to cover said trade-mark and product identifying indicia, whenever desired, and means formed at the free end of and within the longest strip for securing, that portion of the longest strip which is adapted for covering said trade-mark and product identifying indicia, when the same is either employed for covering said trade-mark and product identifying indicia or is positioned to overlie the 20 shortest strip.

2. A retaining band for a package comprising, two elongated strips of fibrous material of different lengths, means for disengageably securing to each other one end of each of the strips and adhesively securing the other end of the shortest strip to the under side of the longest strip, a transverse fold line provided in said longest strip, the longest of said strips containing trade-mark and product identifying indicia thereon, a slit 30 formed transversely through said longest strip 35 to receive and hold the remaining end of said strip, when the same is either folded upon itself to cover said indicia or is positioned to overlie the shortest strip.

3. A band characterized as in claim 2 wherein 40 said remaining end of said strip has a tongue formed therein designed for insertion into said slit.

4. A retaining band to be used with a package containing sanitary napkins comprising, two sections, each having one of its ends disengageably locked to each other, said sections being of different lengths and the shortest of which having its other end adhesively secured to the under-side of the longest section and the longest section having a transverse fold line at the point where the shortest section is adhesively secured, said longest section having trade-mark and product identifying indicia thereon, a transverse slit 45 formed within the longest section and the longest section adapted to be folded upon itself along the transverse fold line to cover said trade-mark and product identifying indicia whenever desired, and a tongue formed at the remaining end of the longest section, said tongue designed for 50 insertion into said slit whether the long section is folded upon itself or is positioned to overlie the shortest strip.

WILLIAM J. WARD.
